(57) **CLAIM**

The ornamental design for a storage container for writing implements, as shown and described.

DESCRIPTION

FIG. 1 is a perspective view of a storage container for writing implements embodying one aspect of our new design;

FIG. 2 is a front elevational view of the storage container for writing implements of FIG. 1;

FIG. 3 is a rear elevational view of the storage container for writing implements of FIG. 1;

FIG. 4 is a left side profile view of the storage container for writing implements of FIG. 1;

FIG. 5 is a right side profile view of the storage container for writing implements of FIG. 1;

FIG. 6 is a top plan view of the storage container for writing implements of FIG. 1;

FIG. 7 is a bottom plan view of the storage container for writing implements of FIG. 1;

FIG. 8 is a perspective view of a storage container for writing implements embodying another aspect of our new design;

FIG. 9 is a front elevational view of the storage container for writing implements of FIG. 8;

FIG. 10 is a rear elevational view of the storage container for writing implements of FIG. 8;

FIG. 11 is a left side profile view of the storage container for writing implements of FIG. 8;

FIG. 12 is a right side profile view of the storage container for writing implements of FIG. 8;

FIG. 13 is a top plan view of the storage container for writing implements of FIG. 8; and,

FIG. 14 is a bottom plan view of the storage container for writing implements of FIG. 8.

The broken line showing in the views is for illustrative purposes only and forms no part of the claimed design.
